EXTENSION SHELF

Filed March 12, 1929

UNITED STATES PATENT OFFICE

VICTOR JONKE, OF OAKLAND, CALIFORNIA

EXTENSION SHELF

Application filed March 12, 1929. Serial No. 346,372.

The invention forming the subject matter of this application relates to shelves, and more particularly to a slidably supported extensible shelf.

5 An object of the invention is the provision of a slidably supported shelf consisting of two longitudinally telescoping sections in which one of said sections is extensible beyond the end of the other of said sections.

10 Another object of the invention is the provision of a shelf consisting of two longitudinally telescoping sections, wherein one of said sections is slidably supported in a frame and the other of said sections is slidably supported in said first section, there being means for limiting the sliding movement of said first section with respect to said frame and further means for limiting the sliding movement of said second section with respect to 20 said first section.

A further object of the invention is the provision of a shelf of the character set forth which is highly useful and simple in construction. Convenience of arrangement, 25 lightness and comparative inexpensive of manufacture are further objects which have been borne in mind in the production and development of the invention.

With the foregoing and other objects in view, which will be made manifest in the following detailed description and specifically pointed out in the appended claim, reference is had to the accompanying drawing for an illustrative embodiment of the invention, wherein:

Fig. 1 is a plan view of the device shown mounted beneath a table top and in which a portion of the table top is broken away so as to more clearly illustrate the details of the 40 shelf;

Fig. 2 is a longitudinal sectional view of the device taken on the line 2—2 of Fig. 1; and

Fig. 3 is a transverse sectional view of the 45 device taken on the line 3—3 of Fig. 1 and shown on an enlarged scale.

Referring to the accompanying drawing wherein similar reference characters designate similar parts throughout, the reference 50 numeral 5 indicates a shelf which is slidably

supported on guides 6 disposed at the opposite longitudinal edges of said shelf. In the present instance, the guides 6 are shown as being secured to the vertical sides 7 of a table 8 in such a manner that the shelf 5 is supported in a horizontal position directly beneath a top 9 of said table and is slidable thereunder. The shelf 5 comprises two sections, a U shaped section 11 and a central section 12 slidably disposed between the legs 13 55 of the said U shaped section and extending therebetween forming a continuous flat upper surface. Sections 11 and 12 are of equal thickness so that both the top and bottom surfaces thereof are flush and form continuous 60 flat surfaces.

In order that the shelf section 12 may be slidably supported by the U shaped section 11, there is provided a substantially T shaped metal plate 14, the head 16 of which extends 70 transversely across the bottom surface of the shelf 5 at the front end thereof and is secured at its ends to the under sides of the opposite legs 13 by means of screws 17. The leg 18 of the plate 14 extends centrally and longitudinally of the shelf 5, and is secured at its end to the under side of the base 19 of the U shaped section 11 by means of screws 21. Means are provided for limiting the sliding 75 outward and inward movement of the shelf 5. Said means comprise downwardly depending stops 22 formed integral with and on the opposite sides of the leg 18. Stops 22 are adapted to abut against the inside edge of a supporting strip 23 which extends transversely 80 across the under side of the shelf 5 and is secured at its ends to the guides 6. It will be seen that the distance between the stops 22 and the inner side of the strip 23 will determine the distance that the shelf 5 may be 85 slidably extended from the table 8. 25 indicates a downwardly turned top edge of the T shaped plate 14 which abuts against the outside edge of the supporting strip 23 and limits the inward movement of the shelf 5. 90

As has been hereinbefore stated, the shelf section 12 is slidable within the U shaped section 11 and independently thereof, so that when the shelf 5 is drawn outwardly to the limit of its movement both of said sections 100

cooperate to form one shelf which may be further extended by drawing out the section 12 beyond the end of the section 11, as is clearly shown in dotted lines in Figs. 1 and 2. 5 In order that the section 12 may be prevented from sliding completely out of the section 11, the same is provided at its end with projections 26 which extend transversely from the opposite longitudinal sides of said section. Numeral 27 indicates a slot cut into the inside edge of each of the legs 13 of the section 11 and forming an abutment 28 at the forward end thereof. The distance that the section 12 will project from the end of the section 11 is determined by the space between the extensions 26 and the abutments 28 at the time when section 12 is in closed position, as is clearly shown in Fig. 1.

20 A further feature of the device is that when the shelf 5 is in its fully extended position the abutment 28 will be slightly outward from the adjacent edge of the table top 9, as is clearly shown in Fig. 1. Now when the section 12 has been fully extended, the projections 26 will engage the abutments 28 which limits the movement thereof so that a portion of the inside end of said section will lie partly under the table top 9, which prevents the two sections 11 and 12 from becoming disengaged.

25 The outer and inner edges of the section 12 are rounded as at 31, which when said section and the section 11 are fully extended, as is clearly shown in dotted lines in Fig. 1, allows the section 12 to be removed, which is 30 accomplished by lifting the outer end of said section and drawing the same from under the table top 9 and from engagement with the abutment 28. Projections 32 similar to the 35 projections 26 extend also from the opposite end of the section 12, and are provided for the purpose of allowing both surfaces of said section to be used.

40 The above mentioned parts are believed to 45 adequately define my invention, and I will now proceed with a description of the operation of the device. The shelf 5 in normal or closed position is clearly shown in full lines 50 in Figs. 1 and 2 as completely covered by the table top 9. When it is desired to slide the shelf into extended position it is merely necessary to grasp the outer end of the section 12 and pull outwardly thereon. This causes 55 both of the sections 11 and 12 to slide outwardly, due to the fact that the frictional engagement between said sections is sufficient to cause the same to move as a unit until the stops 22 engage the transverse member preventing further sliding of the section 11. 60 The shelf as now positioned is sufficiently 65 large for ordinary uses. However, if it is desired to extend the shelf 5, the same is accomplished by sliding the section 12 forward in the section 11 until the projections 26 engage the abutments 28, which prevents fur-

ther movement thereof, and, as has been heretofore stated, the said shelf assumes the position shown in dotted lines in Figs. 1 and 2.

70 I am aware that many changes may be made in the general arrangements and combinations of the several devices and parts, as well as in the details of the construction thereof without departing from the scope of the present invention as set forth in the foregoing specification, and as defined in the following 75 claim, hence I do not limit my invention to the exact arrangements and combinations of the said device and parts as described in the said specification, nor do I confine myself to the exact details of the construction of the 80 said parts as illustrated in the accompanying drawing.

I claim:

85 An extension shelf comprising a cabinet top, guides attached to the under surface of said top, a frame slidable in said guides and comprising a rear transverse member and two side members, a metal plate attached to the under surface of said frame, said side members having the inner surface stepped outwardly providing a wider space therebetween at the rearward end and a shoulder for cooperation with a shelf slidable between said side members and supported between said guides and said top, and depending lugs on said 90 metal plate adapted to cooperate with a transverse member fixedly related between said guides and beneath said frame.

95 In testimony whereof I have affixed my 100 signature.

VICTOR JONKE.
